UNITED STATES PATENT OFFICE.

JOHN F. ANDERSON, OF SAN FRANCISCO, CALIFORNIA.

COMBINATION-TOOL.

1,125,433.

Specification of Letters Patent.

Patented Jan. 19, 1915.

Application filed December 26, 1911. Serial No. 667,757.

To all whom it may concern:

Be it known that I, JOHN F. ANDERSON, residing in the city and county of San Francisco, State of California, have invented 5 certain new and useful Improvements in Combination-Tools, whereof the following is a specification.

My invention relates to improvements in breast drills and has for its object the improvement of the tool generally and also to 10 adapt it for use in grinding valves, more particularly the adaption of it to the hand grinding for automobile valves.

To these ends I provide the tool with a 15 device which will engage the valve so that the latter may be rotated by it, and I further provide it with means whereby at intervals the valve is momentarily withdrawn, the rotation meanwhile continuing so that 20 the position of the valve is continually changed, whereby I prevent the cutting of grooves and cause the valve seat to be ground smoothly and absolutely true.

I further interpose a spring between the 25 valve holding jaws and the rotating mechanism whereby I secure an elastic pressure of the valve during the operation and also provide means to facilitate frequent raising of the valve, thus leaving new grit and oil to 30 run into the bearing surfaces so that the operation is performed more smoothly and quickly.

I also provide the tool with centering means which act as automatic center to hold 35 in alignment while in use.

The particular devices and combinations which constitute my invention are recited in the claims at the end hereof and I wish it understood that I do not desire to be limited 40 except as stated in said claims.

For the better understanding of my invention I have illustrated an embodiment of it in the accompanying three sheets of drawings which I will now proceed to 45 describe.

In the drawings: Figure 1 is an elevation of a drill containing my invention but with the valve engaging jaws omitted; Fig. 2 is a similar elevation taken at right angles to Fig. 1 from the left-hand side thereof; Fig. 3 is a partial elevation on a large scale showing the mechanism for causing the jump or momentary retraction of the chuck out of operative position; Fig. 4 is a similar 55 view of the same parts but with the jump mechanism in operative position; Fig. 5 is a cross section on the line *a*, *b*, of Fig. 3 as

the parts would appear if rotated 90 degrees; Fig. 6 is a detail of the jump mechanism; Fig. 7 is an elevation of the parts 60 shown in Fig. 3 but with the sleeve removed and the parts rotated 90 degrees; Fig. 8 is a similar view to Fig. 4 but shows the parts from the opposite side thereof; Fig. 9 is a cross section on the line *c*, *d* of Fig. 8; Fig. 65 10 is an elevation of the lower part of the tool in operation grinding an automobile valve; Fig. 11 shows the upper part of that portion of the tool shown in Fig. 10 with the centering spider folded and Fig. 12 is 70 an end view from below, of the parts shown in Fig. 11.

In these figures: 1 represents the ordinary shank of a breast drill with the breast piece 2 having mounted thereon the drive 75 gear 3 and the handle 4 by which it is operated; the shank of the handle is made in two parts 5 and 6, telescoping together to vary the leverage or power.

7 is the pinion which engages with the 80 gear 3 and causes the rotation of the shank 8 which carries the chuck 9.

Mounted upon the lower end of the stem or frame is a sleeve 10 secured by a set screw 11 which has pivoted to its lower edge 85 three or more jointed legs 12. The legs are intended as seen in Fig. 10 to rest upon the edge of any convenient orifice through which a valve may be reached and thereby center and steady the tool while in use 90 grinding such valve. When not in use the legs are folded up against the sleeve as is shown more particularly in Figs. 1, 2 and 11.

13 represents a part of an automobile engine cylinder whose valve 14 is being 95 ground; 15 are the jaws which engage the valve. These jaws are pivoted to the end of a shank 16 and are caused to bite by the turn of a screw sleeve 17. The shank is divided just above the threaded portion 16 100 and the two ends are joined by a sleeve 18 and pins 19, one of these pins moves in a slot 20 in the upper piece 21 of the shank and a spring 22 is inserted in this sleeve between the two pieces 16 and 21 of the shank 105 thus giving a spring pressure upon the valve during the operation of grinding. The end 21 of the shank is engaged by the chuck 9 as seen in dotted line, Fig. 10 and rotated by the turning of the latter in the 110 usual manner.

Upon the upper part of the rotating stem of the tool and contiguous to the wheel 3 I mount a short sleeve 23 which is provided

with one or more lugs 24. This sleeve may be made of two pieces stamped to the proper form and secured together by screws or rivets 25, seen more particularly in Fig. 5. 5 Upon the inner face of the wheel 3 and inside the circle of the gear teeth is a cam groove 26 having a short throw section 27. One of the lugs 24 projects into this cam groove and is provided with an anti-friction wheel 28 thus the turning of the wheel 3 will once during each revolution raise the device 23 and with it raise the stem and the chuck and the valve, when it is in use and return the valve again at a little different 10 point of its rotation thus permitting oil and grit to work in and giving a much smoother and truer action to the grinding operation. For the purpose of throwing this pump mechanism out of operation I surround it 20 with a semi-sleeve E which is provided with an angular slot F through which one of the lugs 24 projects, and a spring G shown exclusively in Fig. 3 to lock it in position. This semi-sleeve engages the standard 25 or fixed portion of the tool and thus holds the device 23 in position to engage the groove 26 as it appears in Figs. 4 and more particularly 8 and 9, or to be free therefrom as shown in Figs. 1, 2, 3, and 6 and 30 more particularly 5 and 7, as the case may be. The stem 8 which carries at its lower end the chuck 9 is capable of sliding through the pinion 7 and for this purpose is made of considerable length extending 35 into a hollow in the shank of the tool as shown by dotted lines Fig. 1. The stem may thus be projected more or less to reach otherwise inaccessible points. 29 and 30 represent heads of a sleeve on 40 the stem 8 on which sleeve the device 23 is directly mounted between the heads. The head 29 of the sleeve is milled and the head 30 has a split and tapered section provided with a thread upon which is a milled nut 31. Thus by turning the nut 31, the split 45 end of sleeve 30 may be made to bite the stem 8 which passes through it to hold it firmly against further longitudinal movement, while permitting it to rotate freely. 50 32 is a groove in the stem 8 which is engaged by a projection on the sleeves 29 and 30 to lock them together rotatively. 33 is a sliding bolt operated from a head 55 34 and serving to engage one of a series of notches 35 in the edge of the nut 31 thereby holding the latter while the sleeve is rotated, thus causing the latter to bite. Having thus described in detail the embodiment of my invention what I claim is: 60 1. In a device of the character described, a

shank provided with a swivel section, jaws on said section adapted to engage a valve and screw threaded means for locking said jaws upon said valve.

2. A device of the character described 65 comprising a shank, a swivel section on said shank, jaws pivoted to said swivel section adapted to engage a valve and external means on said swivel section for locking said jaws in operative position.

3. In a drill the combination with the rotating shank thereof, a swivel section on said shank, jaws pivoted to said section and adapted to engage recesses formed upon the flat surface of a valve and a screw threaded 75 sleeve engaging said section and the outer edge of said jaws for locking the same upon said valve.

4. In a drill the combination with the rotating shank thereof having an intermittently moving section, a pair of jaws pivoted to said section and adapted to engage a valve, a sleeve on said section engaging the outer edges of said jaws and lock the same 80 in position upon said valve.

5. In a breast drill the combination with the rotating shank thereof, jaws pivoted on said shank and adapted to engage a valve means for causing said jaws to bite, and an elastic section interposed between said 90 shank and said jaws.

6. In a breast drill, the combination with a rotating member thereof and a fixed member, an adjustable sleeve mounted on the fixed member, legs pivotally secured to said 95 sleeve and adapted to center said drill by engagement with the work.

7. In a breast drill the combination with a rotating stem and a main gear-wheel a groove on said main gear-wheel provided 100 with a depressed portion, a split sleeve on said stem having means adapted to engage said groove and said depressed portion whereby the stem is given a jump at intervals and means to release said engagement 105 and lock said split sleeve in position.

8. In a breast drill the combination with a fixed member and a vertically adjustable member connected to said fixed member, a split sleeve and a nut adapted to clamp said 110 sleeve upon said adjustable member and hold it in a predetermined position.

In testimony that I claim the foregoing I have hereto set my hand in the presence of witnesses, this 20th day of December, 1911. 115

JOHN F. ANDERSON.
